UNITED STATES PATENT OFFICE.

FRIEDRICH HUPE, OF THE UNITED STATES NAVY.

ROTARY ENGINE.

1,138,481.

Specification of Letters Patent.

Patented May 4, 1915.

Application filed January 7, 1915. Serial No. 961.

To all whom it may concern:

Be it known that I, FRIEDRICH HUPE, a citizen of the United States, stationed on board the U. S. S. *Michigan*, have invented 5 certain new and useful Improvements in Rotary Engines; and I do hereby declare the following to be a full, clear, and exact description of the invention, such as will enable others skilled in the art to which it 10 appertains to make and use the same.

The present invention relates to rotary steam engines and consists more particularly in an improved steam engine constructed of a cylinder formed with an abutment, a 15 rotor mounted in the cylinder and swinging pistons carried by the rotor and arranged to be projected by cam-actuated means to coöperate with the abutment and receive the driving fluid to propel the rotor.

20 It is an object of the present invention to provide a steam engine constructed with a cylinder divided into a pair of compartments each formed with a reversely disposed abutment coöperating with oppositely 25 arranged pistons mounted to swing on a rotor and constituting an arrangement adapted to be driven in either a forward or reverse direction.

30 A further object of the present invention resides in providing an improved steam engine which will be constructed of few and simple parts, readily assembled, and adjusted to reduce the wear on the same, thereby prolonging the life of the engine; and which 35 parts may be readily removed and replaced when desired.

With these and other objects in view the invention consists in the novel details of construction and combinations of parts more 40 fully hereinafter disclosed and particularly pointed out in the claims.

In the accompanying drawings forming a part of this application, and in which similar reference symbols indicate corresponding 45 parts in the several views: Figure 1 is an end elevational view, partly in section, of a steam engine constructed in accordance with the present invention. Fig. 2 is a side elevational view of the same. Fig. 3 is a vertical sectional view taken on the line 3—3 of Fig. 1 and looking in the direction of the arrows. Fig. 4 is a substantially horizontal sectional view, partly in plan and illustrating a section through one of the piston spin- 50 dles. Fig. 5 is an enlarged elevational view,

partly in section, of a pair of pistons and associated parts. Fig. 6 is an end elevational view of the same; and Fig. 7 is a fragmentary view of the framework, illustrating in horizontal section, an enlarged detail of the 60 journal boxes.

Referring more particularly to the drawings, the engine cylinder is preferably constructed in two parts 1 and 2, divided vertically and connected together by bolts, or 65 other suitable devices, 3. The cylinder sections 1 and 2 are cast with base portions 4 and 5, whereby the engine may be mounted upon a suitable bed; and the base portions 4 and 5 are formed with pedestals 6 and 7, 70 erected in spaced relation to the engine cylinder. Each cylinder section 1 and 2 is further cast with horizontally-disposed members 8 and 9, coöperating with the respective pedestals 6 and 7 to support therebetween 75 bearing boxes 10, wherein is journaled a main shaft 11.

The rotor 12 of the engine is constructed with a central partition plate 13 for dividing the cylinder into a pair of compartments 80 closed by heads 14 and 15, bolted or otherwise secured to flanges 16 and 17 projecting from the partition 13 to either side thereof, and located in the respective compartments of the cylinder. As disclosed to advantage 85 in Figs. 3 and 4, the cylinder sections 1 and 2 are formed with abutments 18 and 19, disposed to either side of the base of the engine and arranged in reverse relation.

In the partition plate 13 and the cylinder heads 14 and 15 are journaled a plurality of piston supporting spindles 20, more particularly illustrated in Fig. 5 to be provided with a central bearing collar 21 journaled in the partition 13. To either side of the bearing 90 collar 21 are mounted sleeves 22 and 23 adjustably held upon the spindle 20 by set screws 24 and 25. The sleeves 22 and 23 are arranged to support spaced pairs of arms 26 and 27, projecting in opposite directions, and to which are respectively connected companion pistons 28 and 29 operating to either side of the partition 13 in the separate compartments formed thereby. As shown more particularly in Fig. 6, the pistons 28 and 29 are 95 formed arcuate, so as to oscillate with a tight fit through slots provided in the respective flanges 16 and 17 of the rotor, as shown in Fig. 3. The arcuate pistons are preferably connected to the arms 26 and 27 by means of 100 105 110

pin and slot, or other loose connections indicated at 30 and 31 in Fig. 6, and may be adjusted as required.

Each spindle 20 projects beyond the cylinder heads 14 and 15, and is shaped to receive arms 32 and 33 extending in opposite directions, and provided at their outer free ends with rollers 34 and 35 engaging cam tracks 36 and 37, bolted or otherwise secured to the horizontal members 8 and 9 and the respective pedestals 6 and 7 of the engine frame.

Referring now to Figs. 2 and 7 of the drawings, the bearing boxes 10 supported, as above described, between the horizontal members 8 and 9 and the pedestals, are arranged to receive a flanged cage 38 in which is mounted the journal box comprising, preferably, a pair of members 39 and 40 threaded together and inclosing the concentric rings 41 and 42, providing therebetween races for the ball bearings 43. The cage 38 is supported in the bearing box 10 by means of set screws 44, which may be adjusted to center the engine shaft 11, in order to insure the proper positioning of the rotor and pistons within the cylinder.

The abutment 18, in the compartment of the engine cylinder, arranged between the partition plate 13 and head 14, is traversed by intake and exhaust ports, respectively, 46 and 47; and similarly, the abutment 19 of the opposite compartment is traversed by intake ports 49 and 50, the relation of the several ports being disclosed to advantage in Fig. 3.

In operation, the driving medium is introduced either through the intake 46 of the cylinder portion 1, or the intake 49 of the portion 2, accordingly as it is desired to drive the engine in either a forward or reverse direction. The fluid is directed against the piston blades 28 or 29, and acts upon the same to impart movement to the rotor. As the rotor revolves, the rollers 34 and 35 are actuated by the cam tracks 36 and 37 to alternately project and retract the pistons as the abutments are encountered, maintaining the pistons constantly in contact with the inner peripheral edge of the respective cylinder sections 1 and 2. It will be understood that the cam tracks and associated roller and arm connections for the pistons will each coöperate together to insure the proper actuation of the pistons, as the arrangements will be seen to be reciprocal.

It is obvious that those skilled in the art may vary the details of construction and arrangements of parts without departing from the spirit of my invention, and therefore I do not wish to be limited to such features except as may be required by the claims.

I claim:

1. In a rotary engine, the combination of a cylinder, a rotor journaled in said cylinder, a partition constructed with said rotor and arranged to divide the cylinder to provide

a pair of compartments, an abutment located in each of said compartments and formed with intake and exhaust ports, cylindrical flanges projecting from said partition into each of said compartments, cylinder heads for inclosing said compartments connected to said flanges, spindles journaled through said partition and cylinder heads, a pair of pistons mounted on each of said spindles and arranged to operate one in each of said compartments, and means for rocking said spindles to actuate the piston, substantially as described. 70 75

2. In a rotary engine, the combination of a cylinder, a rotor journaled in said cylinder, a partition constructed to rotate with said rotor and arranged to divide said cylinder to provide a pair of compartments, abutments located in said compartments and provided with intake and exhaust ports, cylindrical flanges projecting from said partition and arranged to revolve one in each of said compartments, cylinder heads for inclosing said compartments and connected to said flanges, spindles journaled through said partition and cylinder heads, a sleeve mounted on said spindle one to each side of said partition and connected to move with the same, pistons supported from said sleeves and adapted to be projected through the respective cylindrical flanges into said cylinder compartments, an arm connected to each opposite end of said spindle, and cam means for actuating said arms to rock the spindles as the rotor revolves, substantially as described. 80 85 90 95 100

3. In a rotary engine, the combination of a cylinder built up of a pair of vertically divided sections, means for connecting said sections together, pedestals cast with said cylinder sections, a main shaft journaled in said pedestals, a rotor mounted to revolve with said shaft and constructed with a central partition for dividing the cylinder to provide a pair of compartments, abutments located in said compartments and provided with intake and exhaust ports, and pistons carried by said rotor for coöoperating with the abutments in said compartments, substantially as described. 105 110 115

4. In a rotary engine, the combination of a cylinder built up of a pair of vertically divided sections, means for connecting said sections together, bases cast with said sections, pedestals cast with said sections and erected in spaced relation thereto, horizontal members extending in opposite directions from said cylinder sections and jointed centrally to said pedestals, a main shaft journaled in said pedestals and horizontal members, a rotor mounted on said shaft within the cylinder, and pistons carried by said rotor, substantially as described. 120 125

5. In a rotary engine, the combination of a cylinder built up of a pair of vertically 130

divided sections, bases cast with said sections, pedestals cast with said bases, a main shaft journaled in said pedestals, a rotor mounted on said main shaft and constructed with a partition for dividing said cylinder to provide a pair of compartments, a reversely disposed abutment located in each of said cylinders and provided each with intake and exhaust ports, cylindrical flanges projecting in opposite directions from said partition and arranged to rotate in the respective cylinder compartments, a pair of cylinder heads for inclosing the sides of the compartments and connected to said flanges, a

plurality of spindles journaled through said partition and cylinder heads, separate series of pistons mounted on said spindles to either side of said partition and arranged in reverse relation to correspond with the respective abutments, and means for rocking said spindles to actuate said pistons, substantially as described.

In testimony whereof, I affix my signature, in presence of two witnesses.

FRIEDRICH HUPE.
